MARKING MACHINE

Alfred H. Avery, Malden, Mass., assignor to The
Perfection Marker Company, Cambridge, Mass.,
a corporation of Massachusetts

Application May 14, 1932, Serial No. 611,355

12 Claims. (Cl. 101—316)

This invention relates to machines for marking shoe upper sections or similar pieces of sheet material, and particularly for performing the method of marking described in the Edwards

5 Patent No. 1,639,332, dated August 16, 1927.

In the manufacture of shoes, particularly women's shoes, it is customary to apply ornamental designs to the shoe uppers, as by stitching, perforating or embossing. Present fashions 10 demand that shoe uppers be made of leather, textile fabrics such as silk, satin or velvet, and various other kinds of sheet material. Usually, the ornamental designs are applied to the cut-out sections of the uppers before they are assembled 15 in the shoe; and in the case of stitching, the designs are first marked on the shoe uppers and the marked designs are then followed in the stitching. As explained in said Edwards patent the design may be impressed upon the shoe upper 20 section, or similar article of sheet material, by a marking plate, on which the desired pattern is formed by bosses punched from the material of the plate and disposed in lines, rows or other arrangements to delineate the pattern. The marking 25 plate is then impressed upon the shoe upper section or other piece of work to be marked, with a transfer sheet against the opposite side of work, and the pattern displayed by the bosses will then be printed or impressed on the work. A 30 similar method may be used without the transfer sheet for merely embossing a piece of leather, in which case the marking plate will be embossed in accordance with the desired design, or for perforating the work, in which case the marking 35 plate will be made with bosses in the form of cutting punches of such shape and arrangement as to cut holes or perforations in the work, shaped and arranged according to the desired design.

Printing or marking, perforating and embossing, whether used separately or in various combinations at the same time, are all included in the expression marking as herein used; and the term marking plate is used to designate the plate for applying the design to the work whether the plate is constructed for printing from a transfer sheet, or for perforating, or for embossing, or for any combination of these operations.

One object of the invention is to provide a 50 marking machine having a normally inactive reciprocable press member which is automatically operated to impress the desired design on the work when a platen, supporting the work and the marking plate, is moved into operative relation to the press member, and to stop the press mem-

ber when the platen is moved away from the press member.

Another object of the invention is to provide means by which the marking plate is automatically controlled so as to rise or move away from the platen to permit the placing of the article to be marked upon the platen or permit it to be removed from the platen, when the platen is shifted out from under the press member, and to move the marking plate into operative position overlying the work on the platen when the platen is shifted to operative position under the press member.

Other features of the invention are mechanism for automatically advancing the transfer sheet each time the platen is moved in and out of operating position with relation to the press member; means for detachably and interchangeably mounting the marking plate on the platen and for correctly positioning the same thereon; work-positioning means associated with the platen; and the mechanisms for controlling and actuating the various parts.

These and other features will be herein more fully described and particularly pointed out in the claims.

In the accompanying drawings which illustrate preferred embodiments of the invention,

Fig. 1 is a front elevation of the machine;

Fig. 2 is a plan view partly in horizontal section on line 2—2 of Fig. 1;

Fig. 3 is a side elevation of the machine;

Fig. 14 is a sectional detail of one end of the marking plate shown in Fig. 12;

Fig. 15 is a sectional detail on line 15—15 of Fig. 12; and

5 Fig. 16 is an elevation of the locking bar forming part of the locking plate holder shown in Fig. 12.

Referring first to the form of machine shown in Figs. 1 to 11, the frame of the machine consists 10 of a base 10, adapted to rest upon and be secured to a bench or similar support, and an upper frame 11 in the general form of an arch.

The base 10 is provided at opposite sides with 15 guideways or grooves 12 within which the work-supporting platen, indicated generally at 13, is mounted to slide forward and backward into and out of operative position with relation to a reciprocable plunger or press member 52, carried by the frame 11. The platen 13 is provided at its 20 front end with a handle 14 by which it may be manually moved back and forth along the ways 12. In the drawings the platen 13 is shown occupying its outermost position away from the press member, in which position the machine is 25 at rest.

The body or bed 15 of the platen is preferably a rectangular casting. Near each corner it is formed with a vertical hole 16 (Fig. 6) whose upper portion is of smaller diameter than its lower portion. 30 The lower end of the hole 16 is closed by a plug 17 which serves as an abutment for a coil spring 18 by which a plunger 19 is yieldingly supported with its upper reduced end 20 projecting above the top surface of the body 15 of the platen.

35 Resting on top of the platen 15 is a removable work-positioning plate 21 preferably made of cardboard or similar sheet material and provided near each corner with a small aperture reinforced by an eyelet 22, each eyelet being adapted to be 40 fitted upon the upwardly projecting reduced end 20 of one of the plungers 19. Thus the plungers 19 serve to hold the work-positioning plate 21 in a definite position on top of the platen 15 so that it will not be displaced laterally but can readily be removed when desired. The work-positioning plate 21 is made with a cut-out or recess 23 (Fig. 8) so shaped as to receive and properly to 45 position the piece of work to be marked, such as the vamp or forepart of a shoe upper 24, or other 50 piece of sheet material. As herein illustrated the cut-out 23 of the work-positioning plate 21 is formed with opposite side edges 25, 25 to engage the opposite side edges of the sheet article 24 to 55 position the same laterally, and with end edges 35 to engage the outer end of the article 24 thereby to position the same longitudinally. It is not necessary that the cut-out 23 should exactly conform in all respects to the shape of the article to 60 be marked but it must be of such shape and dimensions that it will receive the article to be marked and will fit it sufficiently closely at a sufficient number of points to position it definitely and accurately to be properly operated upon by 65 the marking plate. It will be understood that for each different shape and size of article to be marked a different work-positioning plate 21 will be used having a cut-out adapted to the size and shape of the work in question.

Near the inner end of the platen 15 (Figs. 2, 70 5, 8 and 11) is a marking plate holder indicated generally at 26, comprising a transversely disposed rock-shaft 27 which rests at its opposite ends within sockets 28 provided in a bracket 15^a secured to the end of the platen body. The bearing 75 ends of the rock-shaft 27 are held within the

sockets 28 by means of detent plates 29 secured in position against the opposite sides of bracket 15^a by screws 30. The screws 30 occupy slots formed in the detent plates 29 so that by loosening the screws and retracting said plates the holder 26 30 can be removed from the platen.

Secured to the upper flattened side of the rock-shaft 27 by means of rivets 31 is a rigid bar 32 (Figs. 7 and 8) and secured to the top side of this bar 32 by the same rivets is a strip 85 of resilient sheet metal 33, which is of greater width than the bar 32 so that its margin extends inwardly beyond the bar as best shown in Fig. 7. The free or projecting margin of the strip 33 is transversely slotted at intervals, as best 90 shown in Fig. 8, to provide a row of spring tongues 34 each of which is embossed to provide a rounded boss or projection 36 upon its under side (Figs. 7 and 8).

The marking plate, which is detachably secured to said rock-shaft, is shown at 37 and is preferably made of a piece of sheet metal such as galvanized iron embossed or otherwise formed to provide marking projections or bosses 38 on its under side (Figs. 8 and 9). The marking plate 100 37 is of such shape and size as to enter the recess or cut-out 23 of the work-positioning plate 21, and is of a shape conforming at least approximately to the shape of the work. At its inner end the margin of the marking plate 37 is bent at 105 right angles in opposite directions on two parallel transverse lines to provide a step 39 and a lip 40 (Figs. 7 and 10), the lip 40 being parallel but offset relatively to the body of the marking plate. The bar 32 forming part of the holder 110 for the marking plate is cut away or stepped upon its inner under side to provide a groove 41 between the bar and rock-shaft 27 into which the lip 40 of the marking plate is inserted. Along the margin of the marking plate 37 near the step 115 39 there is provided a series of holes or sockets 42, each of which is adapted to receive and engage one of the projections 36 on the tongues 34 (Figs. 7 and 10) when the marking plate is attached to the holder. In assembling the marking plate on the holder the lip 40 is inserted in the groove 41 and the plate then pushed home, whereupon the spring tongues 34 will yield until the projections 36 snap into the sockets 42. In removing the marking plate from its holder it 120 is necessary only to pull it forcibly outward, the spring tongues 34 yielding to release the projections 36 from the sockets 42. Thus, the projections and sockets serve both to position the marking plate accurately on its holder and also 125 detachably to secure the marking plate to the holder so that it can readily be removed and replaced by another marking plate of different pattern. It will also be apparent that if desired two or more marking plates can be attached to 130 the holder side by side at the same time, which is sometimes desirable in impressing a plurality of patterns on different parts of the article to be operated upon.

Alongside of the rock-shaft 27 and parallel thereto is a take-up spindle 43, on which is wound one end of a transfer sheet 44 extending from a supply spindle 45, on which is wound a supply roll 45^a of the transfer sheet. The transfer sheet extends across the body 15 of the platen and then underneath the rock-shaft 27 to the take-up spindle 43. The supply spindle 45 is journaled at its opposite end in bearings provided upon a bracket 46 secured to the outer end of the body 15. The handle 14 is fastened 140 145 150

to the bracket 46. A handwheel 47 is provided at one end of the supply spindle 45 and a handwheel 48 is provided at one end of the take-up spindle 43, by which said spindles, respectively, 5 may be manually rotated if desired.

The take-up spindle 43 is supported at its ends within open sockets 50 (Figs. 5, 8 and 11) formed in the top of the sides of bracket 15^a. Normally the spindle 43 is held within the sockets by the 10 detent slides 29. Each detent slide 29 is made with two hooks, 51 and 51^a, the former serving to lock the rock-shaft 27 within its bearing socket 28 and the latter serving to lock the spindle 43 within its bearing socket 50. When the detent 15 slides 29 are retracted, which can be accomplished by loosening the screws 30, both the shaft 27 and the spindle 43 may be removed from the machine.

To prevent accidental rotative displacement of the spindles 45 and 43, leaf springs 48 and 49 fastened to the under side of the body 15 of the 20 platen bear against the under sides of the rolled up transfer sheet wound upon spindles 45 and 43, respectively.

The transfer sheet 44 is similar to carbon paper but its coating is preferably softer than the coating of carbon paper so that the transfer will be made more readily. It is placed on the platen with its transfer surface upward. The coating 30 of the transfer paper is preferably of a suitable color to be readily distinguished from the color of the article to be marked.

Fast on the take-up spindle 43 near one end thereof is a ratchet wheel 95 (Figs. 8 and 11) co-operating with a pawl 96 pivoted at 97 on the machine frame and normally resting by gravity against a stop stud 98 projecting from the frame. The end of the pawl 96 is in the path of the lower side of ratchet wheel 95 so that when the manually moved platen reaches the limit of its outward movement away from the press member, the ratchet wheel 95 engages the pawl and is rotated to the extent of one tooth, thereby advancing the transfer sheet the same distance. 40 When the platen is thereafter shoved inwardly the pawl 96 is idly rocked by the ratchet wheel and as soon as the ratchet wheel passes out of engagement with the pawl the latter is returned by gravity to its normal position against stop 98. 45 Thus, each time the platen is operated in and out its motion is utilized to rotate take-up spindle 43 the distance of one ratchet tooth thereby winding up the transfer sheet 44 on spindle 43 and presenting a fresh unused portion of the 50 transfer sheet to the action of the marking plate for each operation thereof. A stop 53 (Fig. 2) at the side of the platen limits the outward movement of the platen, as hereinafter more fully described, and the pawl 96 is so positioned relatively to the stop that when the platen is arrested by the stop 53 the ratchet wheel 95 and the pawl 96 are in substantially the position 55 shown in Fig. 11.

An important feature of the present invention 60 is that when the platen 13 is shifted to its outermost position away from the press member, the marking plate 37 is automatically raised and held in open position to permit free access to the top of the platen so that the operator may place the shoe upper section or other article which is 65 to be marked in position within the recess 23 of the work-positioning plate 21; and that when the platen is shoved inwardly under the press member the marking plate 37 will be lowered to 70 operative position over the work upon the platen 75

so as to impress the markings upon the work when the press member is operated. Upon again withdrawing the platen from its operative position under the press member the marking plate is again swung upwardly or opened so that the 80 finished work may conveniently be removed by the operator from the platen and a new piece of work inserted in its place. The mechanism for accomplishing this will now be described.

Fixed to one end of the rock-shaft 27, which carries the marking plate, is an arm or cam follower 54 (Figs. 3 and 8) extending upwardly at an incline to cooperate with a cam 55 (Figs. 1, 2 and 3), which is formed by an upwardly bent inclined end of a lever 56 fulcrumed at 57 on top of the base 10 of the machine frame. This lever is yieldingly held in normal position with the cam 55 in the path of arm 54 by means of a leaf spring 58 secured to the side of the base 10. The lever 56 is provided with a laterally and 90 downwardly extending bracket 59 which engages the outer side of the base 10 and serves as a stop to limit the inward swinging movement of the lever 56 under the influence of spring 58.

The free end of bracket 59 is formed with a 100 slot 60 (Fig. 2), against the inner end of which abuts a pin 61 projecting upwards from the stop bolt or latch 53. The stop latch 53 extends through and slides in a hole in the base 10, into the guideway 12 for the platen and into the 105 path of stop shoulder 87 of the platen, and is normally urged by a spring toward its operative position. The stop latch 53 is free to move endwise independently of the lever 56 but when the latter is manually swung outward on its pivot 57 by means of a handle 88 it acts through bracket 110 59 and pin 61 to retract the stop latch 53.

The cam or abutment 55 is normally positioned so that when the platen is moved outwardly and is nearing the end of its movement in that direction the arm 54 on rock-shaft 27 engages the cam 55 thereby rotating the rock-shaft and swinging the marking plate 37 into its raised or open position. The shoulder 87 on the platen engages the stop latch 53 to stop the platen and hold the marking plate 37 in raised position while the platen is in its outward or inoperative position with relation to the press member. When the platen is shoved inwardly toward the press member the arm 54 moves away from the cam 55 thereby permitting the spring 62, aided by gravity, to rock the shaft 27 in the opposite direction and swing the marking plate 37 down into operative position upon the work 24 which is held within the cut-out of the work-positioning plate 21.

Inasmuch as the marking plate 37 is a thin sheet of metal and is sometimes thrown upwardly rapidly and with considerable force by the engagement of arm 54 with cam 55, it is desirable to provide means to arrest the marking plate when raised to its elevated position and to prevent undesirable vibrations thereof. To this end a wire bail 100 (Figs. 1 and 3) is provided, the two side arms of which are supported by the frame 11, with the transverse stretch of the bail in a position to act as an abutment or stop against which the marking plate 37 strikes when raised to its fully open position.

The spring 62 which urges the marking plate towards its lowered or closed position is attached 115 at one end to one of the screws 30, by which the detent slide 29 is held in position, while the other end of the spring extends partly around the under side of rock-shaft 27 and is fastened thereto at 63. The spring 62, therefore, which is normally 120 140 135 150

under tension, at all times yieldingly urges the shaft 27 in a direction to swing the marking plate 37 downward toward closed position on the work. When it is desired to remove the platen 13 from the machine it is only necessary for the operator manually to swing the cam lever 56 side-
15 wise and outwardly thereby removing the cam 55 from the path of arm 54 and at the same time retracting the stop bolt or latch 53. The platen 10 is then free to be drawn forwardly out of the machine.

It is also an important feature of the present invention that the movement of the platen inwardly to operative position under the press member 52 controls mechanism by which the press member is automatically operated to press the marking plate upon the work. This is accomplished by the following mechanism.

In the path of the inner end of the platen body 15 is a stem 64 (Figs. 2 and 3) adjustably fastened to an arm 65 by means of a clamping screw 66. The arm 65 is mounted upon a slide bar 67 supported in a slideway in the base 10 and is provided at its rear end with an abutment pin 68 which bears against arm 65. The opposite end of slide bar 67 is made with a laterally extending lug or abutment 69 to engage with the depending shipper arm 70 of a clutch-controlling lever 71 fulcrumed at 72 (Figs. 1 and 3) on the frame 11 of the machine. The lever 71 actuates an upwardly extending arm 73 carrying at its upper end a wedge-shape cam 74 cooperating with an adjustable member 75 forming part of a clutch mechanism 76 of usual construction. When the member 75 is moved toward the left (Fig. 1) by wedge 74 the clutch is disengaged and when the wedge 74 is disengaged from member 75 the latter is shifted by a spring (not shown) toward the right to set or engage the clutch. The clutch 76 is mounted on a transversely disposed shaft 77 journaled in bearings at the top of the frame 11 and on this shaft 77 is loosely mounted a continuously driven pulley 78 to which one of the clutch members is fixed. When the clutch 76 is set the pulley 78 acts to rotate shaft 77 and when the clutch is thrown out the shaft 77 is at rest. A spring 79 (Fig. 3) acting against the shipper lever 70 yieldingly urges the upper arm 73 toward the clutch-shifting member 75 and also acts through lever 70 to hold the slide bar 67 at the limit of its movement toward the right (Fig. 2). Thus the wedge 74 is normally held in position to engage the clutch-shifting member 75 so that the clutch is normally disengaged and the press member 52, actuated from shaft 77, is normally inactive.

Fast on shaft 77 is an eccentric 80 connected by a pitman 81 with the upper end of the press member 52. It will be understood that the press member is mounted to slide on vertical ways provided on the frame 11 and is reciprocated vertically by shaft 77 and the eccentric connection when the clutch is in engagement.

When the platen 13 is shoved inwardly to the limit of its movement toward its operative position under the press member the rear end of the platen body 15 will engage the end of stem 64, thereby moving the stem 64, arm 65, slide bar 67 and lever 70 toward the left, as viewed in the drawings, whereupon the clutch 76 will be engaged and the press member will be reciprocated vertically by the eccentric 80 until the platen is again pulled forwardly out of operative relation to the press member. The inward movement of the platen is limited by the engagement of the

arm 70 with the frame of the machine and the outward movement of the lever 70 in the opposite direction under the influence of spring 79 is limited by the engagement of the arm 65 on slide 67 with the rear side of the frame 10.

The body 15 of the platen is provided upon its under side with anti-friction rollers 82 loosely mounted within rectangular pockets 83 provided on the under side of the body 15 (Figs. 4 and 5). These anti-friction rollers are held against falling out of the pockets 83 when the platen is removed from the machine by strips of metal 84 fastened by screws to the bottom of the body 15. The rollers are also held against endwise movement in the pockets 83 by small plates 85 fastened to opposite sides of the body 15. The base 10 of the frame is made with a plurality of parallel runways 86 (Figs. 1 and 2) on which the anti-friction rollers 82 travel as the platen is moved back and forth.

The marking plate 37 is provided on its top side with a pad 37^a (Figs. 3, 8 and 10) which may consist of a piece of cardboard of a size and shape corresponding approximately to the size and shape of the marking plate 37. This pad receives the direct impact of the press member 52 during the marking operation. A rubber pad or similar cushion 52^a may be provided on the under side of the press member 52, if desired. In practice the pad 37^a may conveniently and economically be made from the piece of cardboard cut out from the work-positioning plate 21 to form the recess 23. This piece, which would otherwise be waste, may be utilized as the pad by trimming it slightly to fit the marking plate and fastening it, by cement for example, to the top side of the marking plate.

The operation of the machine, which will be evident from the foregoing description, may be briefly summarized as follows: When the platen 10 is pulled forward out of its operative relation to the press member 52 the press member will be at rest or inactive and the marking plate 37 will be held in raised or open position by the engagement of the arm 54 with the cam 55. The operator then places the shoe upper section or other article of sheet material to be operated upon in correct position within the recess or cut-out 23 of the work-positioning plate 21 with the surface which is to be marked downward in contact with the marking surface of the transfer sheet 44. The platen is then shoved inwardly into operative position under the press member 52. During the first part of the inward movement the marking plate 37 swings down to closed position upon the platen overlying the work held within the work-positioning plate 21. Just before the platen reaches its innermost or operative position under the press member, it actuates the shipper lever 70, thereby setting the clutch 76 and causing the press member 52 to descend on top of the marking plate, whose pattern is thereby impressed on the under side of the work by the transfer sheet 44; or directly on the work if no transfer sheet is used. When the press member rises the platen is again manually pulled out to inoperative position whereupon the clutch 76 is disengaged and the movement of the press member is stopped; and when the platen reaches its outermost position the marking plate is swung upwardly to its open position and the operator removes the marked article from the platen. The machine is now in condition to receive another piece of work and the operation is repeated.

In the modified construction illustrated in Figs.

12 to 16 inclusive the transverse rock-shaft 27^a is made with a flat rear side provided with a longitudinal roll of uniformly spaced studs 89, which are adapted to occupy notches 90 provided 5 along the lower edge of a retaining or clamping bar 91. One end of bar 91 is pivoted at 92 to the rock-shaft 27^a and the other end is engaged by a releasable latch 93 pivoted to the rock-shaft at 94. The marking plate 37 is provided 10 at its inner end with a perpendicular flange 39^a formed with notches 94, spaced to correspond with the studs 89, so that when the marking plate is applied to the rock-shaft 27^a, the engagement 15 of the notches 94 with studs 89 will properly position the marking plate and hold it against displacement. After the marking plate has been placed in position on shaft 27^a the clamping bar 91 is swung downward into closed position against the flange 39^a and the latch 93 is engaged with 20 the free end of the clamping bar to hold the parts in place. This detachable connection, like the ones shown in Figs. 7 and 8, permits two or more marking plates to be attached side by side to the rock-shaft at the same time if desired.

25 I claim:

1. A machine of the character described comprising in combination a movable but normally inactive press member, mechanism for actuating the press member, a platen for carrying the article to be operated upon movable into and out of operative relation to the press member, a marking plate pivotally mounted on the platen to swing upwardly to inoperative position away from the platen and downwardly into operative position on the platen, means controlled by the movement of the platen into and out of operative relation to the press member to lower and raise the marking plate, and mechanism automatically controlled by the platen when the platen is moved into its operative relation to the press member to operate the actuating mechanism of the press member.

2. A machine of the character described comprising in combination a movable but normally inactive press member, mechanism for actuating the press member, a platen for carrying the article to be operated upon movable into and out of operative relation to the press member, a marking plate positioned on the platen between the article to be operated upon and the press member when the platen is in operative relation to the press member, means controlled by the movement of the platen out of operative relation to the press member to raise the marking plate away from the platen, and mechanism automatically controlled by the platen when the platen is moved into its operative relation to the press member to operate the actuating mechanism of the press member.

3. A machine of the character described comprising, in combination, a reciprocable press member, a platen for carrying the article to be operated upon movable into and out of operative relation to the press member, a marking plate pivotally mounted on the platen to swing upwardly to inoperative position away from the platen or downwardly into operative position on the platen, and a cam and cam follower associated with the machine frame and the marking plate adapted to control the downward and upward movement of the marking plate when the platen is moved into and out of operative relation to the press member.

4. A machine of the character described comprising, in combination, a reciprocable press

member, a platen for carrying the article to be operated upon movable into and out of operative relation to the press member, a marking plate pivotally mounted on the platen to swing upwardly to inoperative position away from the platen or downwardly into operative position on the platen, a cam member secured to the marking plate, and a coacting cam member secured to the machine frame in a position to engage the cam member on the marking plate and swing the marking plate upward to inoperative position when the platen is moved to its inoperative position with relation to the press member.

5. A machine of the character described comprising, in combination, a reciprocable press member, a platen for carrying the article to be operated upon movable into and out of operative relation to the press member, a marking plate movably mounted on the platen to be raised and lowered upon the platen, and means consisting of an abutment member on the machine frame and a coacting member connected to the marking plate for automatically raising the marking plate away from the platen when the platen is moved out of operative relation to the press member and for lowering the marking plate upon the platen when the platen is moved into operative relation to the press member.

6. A machine of the character described comprising, in combination, a reciprocable press member, a platen for carrying the article to be operated upon movable into and out of operative relation to the press member, a marking plate movably mounted on the platen and shiftable into and out of operative position on top of the platen, an abutment member on the machine frame for shifting the marking plate on the platen, and a stop for limiting the movement of the platen away from the press member, both said abutment member and said stop being movable into inoperative position to permit the removal of the platen from the machine.

7. A machine of the character described comprising, in combination, a reciprocable press member, a platen for carrying the article to be operated upon movable into and out of operative relation to the press member, a marking plate movably mounted on the platen and shiftable into and out of operative position on top of the platen, an abutment member on the machine frame for shifting the marking plate on the platen, said member being movable out of operative position, a stop for limiting the movement of the platen away from the press member, said stop being movable into inoperative position to permit the removal of the platen from the machine, and means common to said abutment member and said stop to cause both to be moved to inoperative position together.

8. A machine of the character described comprising, in combination, a reciprocable press member, a platen for carrying the article to be operated upon movable into and out of operative relation to the press member, a marking plate movably mounted on the platen and shiftable into and out of operative position on top of the platen, an abutment member on the machine frame for shifting the marking plate on the platen, said member being movably out of operative position, a stop for limiting the movement of the platen away from the press member, said stop being movable into inoperative position to permit the removal of the platen from the machine, and means connecting said abutment member to said stop whereby movement of said abutment member

out of operative position will also move said stop to inoperative position.

9. A machine of the character described comprising, in combination, a reciprocable press member, a platen for carrying the article to be operated upon movable into and out of operative relation to the press member, a marking plate movably mounted on the platen and shiftable into and out of operative position on top of the platen, an

10 abutment member on the machine frame for shifting the marking plate on the platen, said member being movable out of operative position, a stop for limiting the movement of the platen away from the press member, said stop being

15 movable into inoperative position to permit the removal of the platen from the machine, means common to said abutment member and said stop to cause both to be moved to inoperative position together and means yieldingly holding said abut-

20 ment member and said stop in their operative positions.

10. A machine of the character described comprising, in combination, a reciprocable press member, a platen for carrying the article to be operated upon movable into and out of operative relation to the press member, a marking plate, a

25 marking plate holder rotatably mounted on the platen, to which the marking plate is detachably secured, and an abutment on the machine frame controlling the rotation of said holder so as to swing the marking plate to raised and lowered

30 positions in response to movements of the platen

away from and toward its operative position with relation to the press member.

11. A machine of the character described comprising, in combination, a reciprocable press member, a platen for carrying the article to be operated upon movable into and out of operative relation to the press member, a marking plate, a marking plate holder rotatably mounted on the platen, to which the marking plate is detachably secured, means yieldingly urging rotation of the holder in a direction to swing the marking plate toward the platen, and an abutment on the machine frame controlling the rotation of said holder so as to swing the marking plate to raised and lowered positions in response to movements of the platen away from and toward its operative position with relation to the press member.

12. In a machine of the character described, a reciprocable press member, a platen movable into and out of operative relation to the press member, a marking plate movably mounted on the platen, a transfer sheet extending over the platen and underneath the marking plate, a supply roll mounted at one end of the platen on which a supply of the transfer sheet is wound, a take-up roll at the opposite end of the platen by which the transfer sheet is advanced and wound up, and mechanism controlled by the movement of the platen with relation to the press member to operate the take-up roll and advance the transfer sheet each time the platen is operated.

ALFRED H. AVERY.
